FILL CAP

William N. Glab, Dubuque, Iowa, assignor to
 Morrison Bros., Dubuque, Iowa, a corporation of
 Iowa

Application March 19, 1934, Serial No. 716,258

10 Claims. (Cl. 220—55)

The present invention relates to a fill cap and will be herein described as a quick opening fill cap for truck tanks.

Truck tanks, such for example as are utilized for the transportation and delivery of gasoline, fuel oil and the like, in order to be economically operated, must be provided with means for quickly replenishing the empty tanks, so that the inactive time element of such trucks may be reduced to a minimum. This is especially true of the lighter truck tanks used for delivering gasoline, fuel oil and the like to retail trade, small filling stations, home garages and domestic fuel oil tanks, where such trucks are filled several times a day.

The tank must be provided with fill caps which prevent evaporation and gas leakage, which must be quickly opened and closed, and which must be so constructed as not to accidentally open because of vibration incidental to the operation of the trucks along the streets and roads.

The present invention is directed to, and has for an object, a fill cap which may be quickly and easily opened and closed by simple movement of a handle, and which is locked in closed position so as not to accidentally open.

Another object of the invention is to provide a fill cap, including a neck and a lid, which neck may be welded to any tank to equip such tank with the present cap.

A further object of the invention is to provide a fill cap construction including a neck and a lid, wherein the lid is provided with means for locking engagement with the neck and also with a handle for actuating such locking means.

A still further object of the invention is to provide a fill cap construction including a neck and a lid, with cam actuated locking means carried by the lid, together with an actuator, and the provision of means for retaining the actuator against movement in unlocking direction after it has been moved to effect locking engagement of the lid with the neck.

Another and still further object of the invention is to provide a fill cap construction including a neck and a lid hinged to the neck, lugs on the neck, pawls on the lid, an actuator on the lid for moving the pawls into and out of locking engagement with the lugs, means for retaining the pawls in locked engagement with the lugs, and a sealing gasket in the lid for contacting the neck to seal the joint between the lid and neck.

The above, other, and further objects of the invention will be apparent from the following

description, accompanying drawing, and appended claims.

The accompanying drawing illustrates a fill cap constructed in accordance with the principles of the present invention, and the views thereof are as follows:

Figure 1 is a side elevational view of a fill cap constructed in accordance with the principles of the present invention, and showing in full lines the lid in closed and locked position, and in dotted lines the lid in open position.

Figure 2 is a top plan view of the structure of Figure 1 showing in full lines the handle in locked or closed position and in dotted lines the handle in open or unlocked position.

Figure 3 is an enlarged vertical sectional view, taken substantially in the plane of line III—III of Figure 2, with the handle in open or unlocked position.

Figure 4 is a bottom plan view of the illustrated form of actuator or cam of the present invention, and showing a fragmental portion of the handle.

Figure 5 is a top plan view of the lid, with the actuator removed, illustrating the action of the locking pawls, and showing these pawls in full line and unlocked position and in dotted lines in locked position.

Figure 6 is a fragmental view of the hinge connection between the lid and the neck showing the hinge pin as having play in the ears of the neck, so that the lid may be moved tightly against the neck in the direction of the axis of the neck.

The drawing will now be explained.

The present invention is herein illustrated as including a neck 1 and a lid or cover 2. The neck 1 may be suitably welded to any tank for applying the fill cap of the present invention to such tank.

The neck 1 is provided with rearwardly extending ears 3 and 4 in which are elongated slots 5 for receiving a hinge pin 6. Pin 6 passes through suitably disposed apertures in ears 7 and 8, integral with the lid 2. A sleeve 9 may be interposed about the pin 6 and between the ears 7 and 8. The pin 6 is prevented from displacement by a cotter pin 10 passing through the sleeve 9 and the pin 6.

The lid 2 has an upstanding boss 11 formed integrally with it, which is bored at 12 to receive a suitable vent. As the vent forms no part of the present invention the bore 12 is shown as closed by a cap 13.

The under surface of the lid 2 is provided with an annular channel 14 in which is inserted a gasket 15 for resting against the upper margin of the neck 1 when the lid is thereagainst applied, 5 for sealing the joint between the lid and the neck.

The neck 1 is shown as provided with out-standing lugs 16 and 17, shown as disposed on opposite sides of the neck from the center of 10 the same, which lugs may be integrally formed with the neck or may be separately formed and permanently connected to the neck as desired.

The lugs 16 and 17 are herein illustrated at substantially diametrically opposite points.

15 The lid 2 carries upstanding pivots or studs 18 and 19 which may be formed as part of the lid when cast, or if otherwise made, may be inserted. Inasmuch as these studs are desirably of different material of which the lid is made 20 they preferably are inserted in the lid.

Locking members, herein referred to as pawls, are pivotally disposed on the pivots 18 and 19. The pawls are similar in construction and therefore will be designated by the same reference 25 character. The pawls 20 are provided with downturned ends 21 having a lip or foot 22 projecting laterally and with the upper surface preferably inclined. The inclined surfaces of the lip 22 engage the under surfaces of the lugs 30 16 and 17 for drawing the lid 2 tightly against the neck 1 as will be hereinafter described. The inner ends of the pawls 20 are provided with up-standing projections or pins 23. The downturned extremities 21 of the pawls 20 lie adjacent the exterior of the neck 1 so that as the 35 pawls are actuated, the lips 22 will be moved into or out of engagement with the lugs 16 and 17.

For rocking the pawls 20 about the pivots 18 40 and 19, an actuator, consisting in the present instance of a hood 24 having a handle 25 as a part thereof, is provided with a central aperture 26 to surround the upstanding boss 11 of the lid 2. The underside of the hooded member 24 is provided with cam slots 26 and 27 (see Figure 4) for receiving the pins 23 of the pawls 20. The hooded member 24 is applied over the boss 11 of the lid 2 with the cam slots 26 and 27 on its underside so that the slot 26 receives the pin 23 45 on the lower pawl of Figure 5 and the slot 27 receives the pin 23 of the upper pawl of Figure 5. The hooded member or actuator is secured to the boss 11 in any suitable manner, a spring ring 28, engaging a groove 29 in the boss 11, is herein 50 illustrated as the means for securing the actuator in place on the lid 2.

The full line position of the handle 25 of Figure 2 is the position occupied by the actuator when the pawls are in locking or closed engagement with the lugs 16 and 17 and the dotted line position of the handle of this figure shows the open or unclosed or unlocked position.

It will be observed that as the handle 25 is moved from the dotted line position of Figure 65 2 to the full line position of the figure, the engagement of the cam slots 26 and 27 of the pins 23 of the pawls 20 will oscillate these pawls about the pivots 18 and 19 to increase the distance between the pins 23 of the pawls and thus 70 move the lips 22 thereof underneath the lugs 16 and 17. Because of the inclined surface engagement between the lugs 16 and 17 and the lips 22 of the pawls 20 the lid 2 is forced tightly 75 against the neck in the direction of the axis of the neck to thus efficiently seal the joint between

the neck and the lid. Movement of the handle in the opposite direction will draw the pins 23 together or towards each other thus releasing the engagement of the lips 22 with the lugs 16 and 17 to unlock the lid whereupon it may be swung back from the neck about the hinge pin 6.

In order to lock the lid in closed position any suitable means may be provided. There is herein illustrated a spring pressed ball 30 carried in a pocket 31 formed on the top side of the lid and urged against the underside of the hooded member 24 by the spring within the pocket. The underside of the hooded member 24 is provided with a recess 32 into which the ball 30 snaps, when the hooded member is moved to the extent 15 of movement in locking direction, whereby the hooded member is then locked against accidental movement. The tension of the spring, actuating the ball 30, is such as to enable manual manipulation of the hooded member but is sufficient 20 to prevent any vibration from dislodging the hooded member when locked in the manner described.

The provision of the elongated recesses 5 in the ears 3 and 4, for the hinge pin 6, permit 25 slight relative movement of the lid 2 with respect to the neck 1 in other than arcuate travel so that the lid may be tightly clamped against the neck 1 without imposing undue strain on the hinge pin or any of the hinge parts.

It will be observed that the fill cap of the present invention is constructed to effect tight sealing between the lid and the neck and that the provision of the manually operable hooded member 24 causes quick action of the pawls 20 30 into and out of locking engagement with the lugs 16 and 17.

The construction of the parts is such that all are freely operable when sufficient hand pressure is applied to the handle 25 for unlocking 40 or locking the structure.

The neck 1 is shown as provided with a flange 33 which may be welded to a tank in any suitable manner.

The provision of the gasket 15 makes a vapor 45 and dust tight joint between the lid and neck.

The parts are so designed and constructed as to enable production of the fill cap of the present invention at low manufacturing costs.

Any suitable air vent may be applied to the 50 bore 12 as occasion may require.

The invention has been described herein more or less precisely as to details, yet it is to be understood that the invention is not to be limited thereby, as changes may be made in the arrangement and proportion of parts and equivalents may be substituted, without departing from the spirit and scope of the invention.

The invention is claimed as follows:

1. A fill cap comprising in combination with a neck, a removable lid, lugs on said neck, oscillatable cam means supported on said lid, and pawls oscillatably supported on said lid by substantially vertical pivots and swingable by said cam means in substantially horizontal planes 65 about said pivots into and out of hooking engagement with said lugs.

2. A fill cap structure including a neck and a lid, two pawls pivoted to said lid to swing parallel to the same, manually operable means on said lid for swinging said pawls, and means on said neck for hooking engagement by said pawls when swung in one direction, the cooperating portions of said pawls and said hook engaging means being inclined in such manner that the 75

lid is tightened against said neck as said pawls are swung in locking direction.

3. A fill cap construction including a neck and a lid, two pawls pivoted to said lid to swing parallel to the same, cam means on said lid operatively connected to said pawls to swing the pawls in locking direction substantially parallel to said lid when the cam is moved in one direction and to swing the pawls in unlocking direction when the cam is moved in the opposite direction, and means on said neck engageable by said pawls when said cam is moved in said one direction, the cooperating portions of said pawls and the pawl engageable means on the neck being inclined circumferentially of the neck to tighten the lid against the neck when said pawls are swung in locking direction.

4. A fill cap construction comprising a neck and a lid, a lug on said neck, a pawl pivoted on said lid and having a part for engagement with said lug, and means on said cap for swinging said pawl circumferentially of the lid into and out of engagement with said lug, the cooperating surfaces of said pawl and said lug being inclined circumferentially of the neck to tighten said lid against said neck as said pawl is swung in locking direction.

5. A lock for a fill cap, including in combination with a neck and a lid, pawls oscillatably mounted on said lid, projections on said neck, said pawls having feet for engaging the under surfaces of said projections, the engaging surfaces of said projections and feet being inclined to draw the lid tightly against said neck when said pawls are swung to locking position, and means on said lid for oscillating said pawls.

6. A lock for a fill cap, including in combination with a neck and a lid, pawls oscillatably mounted on said lid, projections on said neck, said pawls having feet for engaging the under surfaces of said projections, said pawls having upstanding pins thereon, an oscillatable member having cam slots in it receiving said pins for oscillating said pawls into and out of engagement with said projections, and a handle for oscillating said member.

7. A lock for a fill cap, including in combination with a neck and a lid, pawls oscillatably mounted on said lid, projections on said neck,

said pawls having feet for engaging the under surfaces of said projections, said pawls having upstanding pins thereon, an oscillatable member having cam slots in it receiving said pins for oscillating said pawls into and out of engagement with said projections, a handle for oscillating said member, and means for preventing accidental movement of said member in unlocking direction when it has been moved to locking position.

8. Means for quickly locking and unlocking a lid with respect to a neck, including in combination a lid and a neck, lugs on said neck, pawls oscillatably supported on said lid by pivots substantially perpendicular to said lid, said pawls having overhanging extremities for engaging said lugs, the cooperating portions of said lugs and extremities being inclined in such manner that the lid is tightened against the neck as said pawls are swung in locking direction, and manually operable means on said lid for oscillating said pawls.

9. Means for quickly locking and unlocking a lid with respect to a neck, including in combination a lid and a neck, lugs on said neck, pawls oscillatably supported on said lid by pivots substantially perpendicular to said lid, said pawls having overhanging extremities for engaging said lugs, the cooperating portions of said lugs and extremities being inclined in such manner that the lid is tightened against the neck as said pawls are swung in locking direction, manually operable means on said lid for oscillating said pawls, and means for preventing retrograde movement of said last mentioned means when said pawls are in locking engagement with said lugs.

10. A fill cap comprising in combination with a neck, a removable lid, lugs on said neck, pawls oscillatably mounted on said lid on vertical pivots to swing substantially parallel to said lid, the outer extremities of said pawls having overhanging feet for engaging underneath said lugs when said pawls are oscillated in locking direction, and a member pivoted on said lid for oscillating said pawls into and out of locking engagement with said lugs.

WILLIAM N. GLAB.
